Patented Dec. 10, 1963

197,075

GAME CLUB

Eusebio Felix Acevedo, 751 S. Williamson,
Los Angeles, Calif.

Filed May 20, 1963, Ser. No. 74,969

Term of patent 14 years

(Cl. D34—5)

FIG. 1 is a perspective view of a game club showing my new design;

FIG. 2 is a reduced side elevational view;

FIG. 3 is a side elevational view taken at right angles to the view of FIG. 2;

FIG. 4 is a top plan view thereof; and

FIG. 5 is a view of the opposite or handle end.

I claim:

The ornamental design for a game club, as shown.
